UNITED STATES PATENT OFFICE.

WILLIAM M. MITCHELL, OF LOUISVILLE, KENTUCKY, AND GEORGE A. JOHNSON, OF MARION, INDIANA, ASSIGNEES TO POSITIVE RAIL ANCHOR COMPANY, OF LOUISVILLE, KENTUCKY, A CORPORATION OF VIRGINIA.

RAIL-ANCHOR.

1,032,019.

Specification of Letters Patent.

Patented July 9, 1912.

Application filed December 16, 1910. Serial No. 597,704.

To all whom it may concern:

Be it known that we, WILLIAM M. MITCHELL, a citizen of the United States, residing at Louisville, in the county of Jefferson and State of Kentucky, and GEORGE A. JOHNSON, a citizen of the United States, residing at Marion, county of Grant, State of Indiana, have invented certain new and useful Improvements in Rail-Anchors, of which we do declare the following to be a full, clear, and exact description, reference being had to the accompanying drawings, forming part of this specification.

Our present invention has relation more particularly to that class of rail anchors in which there are jaws for engaging the base flanges of the rail, these jaws being adapted to be brought into wedging engagement with the rail flanges and being connected together by a suitable bar or part extending beneath the rail. A rail anchor of the type to which our invention is particularly applicable, is shown in Letters Patent No. 915,655, granted to Benjamin B. Betts, March 16, 1909.

The object of the invention is to provide improved means whereby the anchor, after it has been moved to position for use upon the rail, may be securely locked or held in such position against danger of accidental or mischievous loosening or displacement, and to this end the invention consists in the features of novelty hereinafter described, illustrated in the accompanying drawings and particularly pointed out in the claims at the end of this specification.

Figure 1 is a plan view of a rail anchor embodying our invention, the anchor being shown in the position which it occupies as it is being applied to the rail. Fig. 2 is a view similar to Fig. 1, but showing the anchor after it has been turned to tightly wedge its jaws upon the base flanges of the rail. Fig. 3 is an end view of the parts shown in Fig. 2. Fig. 4 is a plan view of an end portion of the anchor after its end has been hammered down to engage the edge of the rail flange. Fig. 5 is an end view of the parts shown in Fig. 4. Fig. 6 is a view similar to Fig. 4, but showing a modified form of the invention. Fig. 7 is an end view of the parts shown in Fig. 6. Fig. 8 is a view similar to Fig. 4, but showing a modified form of the invention.

In the drawings, A designates a railway rail and B denotes one of the ties whereon the rail rests. The preferred form of our invention comprises a transverse bar C adapted to extend beneath the base of the rail A from side to side thereof. At one end of this bar C, and preferably formed integral therewith, is a long arm or abutment D that extends downwardly and forwardly, so that when the anchor is in position for use this abutment will engage a side of one of the ties B. At the end of the bar C, adjacent the abutment D, there is formed a jaw E between which jaw and the bar C is a cavity or space adapted to receive one of the flanges *a* of the rail A, and the inner edge of the jaw E is shown as inclined outwardly toward the abutment D, the object of which will presently appear. Preferably, the jaw E is reinforced or strengthened by ribs *e* cast integral therewith, these ribs extending around the jaw, as shown by the several views of the drawings. At its opposite end the bar C is provided with a jaw F adapted to engage the flange *a'* of the rail A, and between this jaw and the underlying part of the bar C is formed a space or cavity to receive the rail flange *a'*. As shown, the jaw F is strengthened or reinforced by ribs *f* formed integral therewith. The outer end of the jaw F is provided with a locking tongue or flange F' which, as shown by Figs. 1 and 3, extends normally in line with the jaw F and is formed integral therewith. This locking flange or tongue F', while shown as extending normally in line with the jaw F, is intended to be bent downwardly with respect thereto, after the anchor has been placed in position for use upon the rail, in order to firmly lock the anchor in position for use and guard against all danger of its accidental or mischievous loosening or displacement.

In order to enable the locking flange or tongue F' to be more readily bent down, under the blows of a hammer, into position to engage the outer edge of the rail base flange *a'*, the metal between the locking tongue or flange F' and the remainder of the jaw F is weakened, as by slotting, grooving or thinning the metal between such parts. In the preferred form of our improved anchor, shown in Figs. 1 to 5 of the drawings, the tongue or flange F' is

separated slightly from the body portion of the jaw F by a long slot f⁴.

In order to enable the tongue or flange F' to be forced down into engagement with the outer edge of the rail base flange a', we prefer to form the upper face of the tongue or flange F' with a raised lug F² adapted to receive the blows of a hammer.

When our improved anchor above described is to be applied to a rail, the body portion or bar C of the anchor is passed beneath the rail between two ties and the jaw F and the tongue or flange F' is forced over the base flange a' of the rail until the outer edge of the rail base flange a' is parallel with and adjacent to the outer wall f³ of the cavity beneath the jaw F, the abutment D being at such time beneath the rail base. When the parts are in such position, (see Fig. 1) the outer edge of the opposite rail base flange a will be parallel with and adjacent to the inclined inner edge e' of the jaw E. The jaw E is then lifted until its upper part extends slightly above the outer edge of the rail base flange a and the anchor is then turned in the direction of the curved arrows, Fig. 1, until the jaws E and F are firmly wedged upon the rail base flanges a and a', respectively. At such time the free end of the arm or abutment D is brought to bear against the side of the tie B. The tongue or flange F' will then extend over the space between the outer edge of the rail base flange a' and the outer wall f³ of the cavity beneath the jaw F and the tongue or flange F' can then be forced downward into engagement with the outer edge of the rail base flange a', as shown in Fig. 5, by blows of a hammer delivered upon the top of the up-standing lug F². When the tongue or flange F' is thus forced to the position shown in Fig. 5, it will firmly bear against the outer edge of the rail base flange a' and will securely lock the anchor in such manner that it cannot be turned in a direction opposite that indicated by the curved arrows (Fig. 1) and, hence, cannot become loose upon the rail.

In the modified form of the invention illustrated in Fig. 8 of the drawings, a tongue or flange F' is shown as separated from the body of the jaw F by a slot f⁵ that extends transversely of the jaw F. While this construction is not deemed as desirable as that hereinbefore described, it will nevertheless be seen that the tongue or flange F' can be more readily forced downward into the space between the outer wall f³ of the jaw cavity and the outer edge of the base flange a' of the rail than would be possible if no such slotting or weakening of the metal between the tongue F⁴ and the jaw F were made.

In the modified form of the invention illustrated in Figs. 6 and 7, the construction

of the anchor is very similar to that first described, except that instead of separating the tongue or flange F' from the body of the jaw F, by means of an open slot, the tongue or flange F' is separated from the body of the jaw F by reducing the thickness of the metal between the tongue or flange F' and the body of the jaw F. This thinning of the metal is accomplished by forming a groove or channel f⁶ extending between the tongue or flange F' and the body of the jaw F, and this can be readily done in the operation of casting the anchor, as it will be understood that the anchor is preferably formed as a malleable iron casting. The anchor is set upon the rail in the manner hereinbefore described and, after the anchor has been brought to the position shown in Fig. 8 of the drawings, the tongue F' is forced downward by blows from a hammer to cause it to bear against the outer edge of the base flange a' of the rail, so as to occupy a position like that illustrated in Figs. 4 and 5 of the drawing. Obviously, the up-standing lug F² may be used upon the tongues or flanges of the several forms of anchors hereinbefore described.

Manifestly, the precise details of construction above set out may be varied without departure from the spirit of the invention; and it will be understood also that the term "anchor" as herein employed is meant to cover not merely a device extending between the ties, as in the precise form of anchor shown, but, as well also, tie-plates or like devices that are adapted to act as anchors to prevent the creeping of the rails.

Having thus described our invention, what we claim as new, and desire to secure by Letters Patent, is:—

1. A rail anchor comprising a part adapted to extend beneath the base of the rail and having at its ends jaws to grip the base flanges of the rail, said jaws being adapted to be turned in one direction to grip said flanges and having a flexible tongue or flange formed upon one end of the upper overhanging part of one of said jaws, said tongue or flange being adapted to be bent downward toward the body of the anchor to engage with the edge of the rail base flange.

2. A rail anchor comprising a part adapted to extend beneath the base of the rail and having jaws to grip the bottom rail flanges, one of said jaws having at its end and upper side a flexible tongue or flange adapted to be bent downward into engagement with the edge of the adjacent rail flange, said jaw being channeled or slotted between said tongue or flange and the body of the jaw to permit the tongue or flange to be more readily bent.

3. A rail anchor comprising a part adapted to extend beneath the base of the rail

and having jaws to grip the bottom rail flanges, said jaws being adapted to be turned in one direction to tighten their grip upon the base flanges of the rail and to be turned in the opposite direction to release them from the rail, the upper overhanging part of one of said jaws having a flexible tongue or flange extending normally in substantial alinement therewith and being adapted to be bent downward to engage with the edge of the adjacent rail base flange.

4. A rail anchor comprising a part adapted to extend beneath the base of the rail and having jaws to grip the bottom rail flanges, one of said jaws being adapted to be turned in one direction to tighten its grip upon the rail flange and to be turned in the opposite direction to loosen its grip upon the rail flange, said jaw being provided at one end with a flexible tongue or flange, the upper part of said jaw being slotted or channeled to permit said tongue or flange to be more readily bent into engagement with the edge of the base flange of the rail, in order 20 to prevent the loosening of the anchor.

5. A rail anchor comprising a part adapted to extend beneath the base of the rail and having jaws to grip the bottom rail flanges, one of said jaws having at its end and upper side a flexible tongue or flange adapted to be bent downward into engagement with the edge of the rail flange and having an upwardly projecting lug on the end of said tongue or flange to receive hammer blows.

35 6. A rail anchor comprising a part adapted to extend beneath the base of the rail and having jaws to grip the bottom rail flanges, one of said jaws having upon its upper side and at one end a flexible tongue or flange adapted to be bent into engagement with the edge of the adjacent rail flange, there being a groove or channel adjacent said tongue or flange and extending in a direction transverse to the body of the 40 anchor to permit said tongue or flange to be bent into engagement with the edge of the rail flange.

7. A rail anchor comprising a part adapted to extend beneath the base of the rail and 50 having jaws to grip the bottom rail flanges, one of said jaws having its upper side arranged to obliquely overlap the rail flange when in position for use, the outwardly ex-

tending end of the upper part of said jaw having a flexible lip adapted to be bent 55 down into the space between the outer edge of the rail flange and the body of the jaw, after the anchor has been turned into position for use.

8. A rail anchor comprising a bar adapted to extend beneath the base of the rail and having jaws formed integral with its ends to engage the base flanges of the rail and having an offset at one end to engage a tie, the jaw at the end farthest from said offset having a flexible tongue or flange forming a portion of its upper overhanging part and adapted to be bent downward into engagement with the edge of the rail flange after the anchor has been turned into position for 70 use.

9. A rail anchor comprising a bar adapted to extend beneath the rail base and having at one end an offset to engage a tie and having at each of its ends a jaw to engage 75 a base flange of the rail, said offset and jaws being formed integral with said bar, one of said jaws having at one end of its upper side a flexible tongue or flange provided at its end with a raised lug to receive the blows 80 of a hammer in order to bend said tongue or flange into engagement with the outer edge of the rail flange.

10. A rail anchor comprising a bar adapted to extend beneath the base of the rail and 85 having jaws to grip the bottom rail flanges, one of said jaws having at its upper part and at its end a flexible tongue or flange extending over the cavity that receives the base flange of the rail, said cavity being of 90 such shape that when said jaw is turned to position for use, there will be a space between the outer edge of the rail flange and the outer wall of the jaw cavity into which space said tongue or flange may be bent 95 downward to hold the anchor against accidental displacement.
